SUPERPOSED RECORD STRIP AND METHOD
OF REGISTERING AND ALIGNING THE
SAME

John Q. Sherman, Dayton, Ohio

Application October 8, 1936, Serial No. 104,593

17 Claims. (Cl. 282—12)

This invention relates to marginally punched manifolding material having the feed holes there-in distinctively arranged and a correlated pin type feeding device operatively engageable therewith for progressively advancing the material past a writing position in which succeeding sets of forms on superposed strips of material will be presented in uniformly registered and aligned relation.

It has long been the practice to provide in the margins of strips or sheets of manifolding material aligned successions of spaced feed holes in which are engageable similarly spaced pins of a traveling pin type feeding device by which superposed strips of material are simultaneously advanced past a writing or impression receiving position.

Great care is exercised in the manufacture of manifolding forms to insure accuracy and uniformity of the relation of succeeding forms with the accompanying feed holes. However unequal expansion and contraction of the material as well as mechanical inaccuracies of the feeding action of the printing press by which successions of forms are imprinted on continuous webs or strips of material causes a slight differential spacing of the forms and corresponding forms of different strips will fail to register throughout the strips when the strips are superposed one on another. While the error or variation may be infinitesimal between succeeding forms, the error is cumulative and the degree of variation progressively increases with advancement of the strips to such extent that in the course of feeding a number of sets of forms they may become so far out of registry as to falsify entries produced on underlying copies by causing such entries to appear in a different line or space or in association with data other than that with which the entry appears upon the original copy.

Therefore in order to insure accuracy of registry and alignment of forms upon separate superposed strips it is necessary that the strips be repeatedly slidingly adjusted one relative to another as succeeding record receiving areas approach the writing position.

Modern commercial usage of printed forms with relatively narrow spacing of lines and laterally restricted columnar spaces necessitates more exacting requirements as to registry and alignment of superposed forms. Some attempt has been made heretofore to effect more frequent adjustment of superposed strips by more closely spacing the feed holes and increasing the number of feeding pins engageable therein. Such method however introduces other difficulties equally as ob-

jectionable, including the decrease of strength of the punched margins of the record material and resulting reduced resistance to pulling strain with greater liability of the holes to tear out, whereas the modern commercial requirement for increased numbers of copies materially increases the frictional resistance and subjects the material to greater pulling strain. The closer spacing of the holes also increases the number of pins simultaneously engaged with the record strips and therefore restricts the range of relative adjustment. It is desirable to have a minimum number of pins engaged at any one time in order that the relative movement of the strips induced by the engagement of one pin may not be resisted by another pin.

For the purpose of distributing the strain upon the record material and effecting a more nearly continuous and uniform registering adjustment by which the strips or sheets may be automatically aligned and registered transversely as well as longitudinally the present invention involves the rearrangement of the marginal feed holes and a corresponding arrangement of feeding pins engageable therein in staggered relation. The feed holes and corresponding pins are relatively offset in directions either or both longitudinally and transversely of the strips or sheets. The feed holes at opposite sides of the strips are longitudinally staggered so that the feed holes of the respective series are not exactly opposite each other but those at one side of the strips will be in advance of those at the opposite side thereof. Thus the feeding pins and the holes in the strips in which those pins engage will pass a given line alternately at one side and then the opposite side of the strip, transmitting thereto more frequent feeding impulses to effect a more uniform advancement and readjustment of the superposed strips and at greater frequency without weakening the material by closely spacing the holes.

The succeeding feed holes of the longitudinal series at each side of the strips are likewise staggered laterally out of direct line. The transverse staggering of the feed holes serves to align the strips laterally and the engagement of the pins in the feeding offset holes imparts a slight jogging influence transversely of the strips first in one direction and then in the other in combination with the advancement in a longitudinal direction to insure accurate registry of the strips longitudinally and transversely. Furthermore the lateral offsetting or staggering of the holes out of direct alignment causes the feeding or pulling strain to be shifted and increased

the distance between the holes in direct line to thereby increase the resistance of the material to such pulling tension.

The offset or staggered relation of the feed holes 5 may occur in different combinations, as for example, the holes at the opposite sides of the strips may be disposed in transverse alignment or they may be staggered so that the holes at one side are in advance of those at the opposite side. Likewise they may be so arranged that corresponding holes at the opposite margins of the strips are both offset inwardly and the succeeding holes both offset outwardly in alternating relation. In lieu of such relation corresponding holes at the opposite margins of the strips may be offset inwardly at one side and outwardly at the opposite side, both in the same direction, and the succeeding holes likewise are offset or staggered both in the opposite direction. The alternate holes may 10 be offset either inwardly or outwardly of a given line on which the remaining holes are located.

The object of the invention is to improve marginally punched manifolding material and the pin type feeding devices usable therewith whereby such material and feeding devices may not only be economically manufactured but will be more efficient in use, positive in operation, uniform in action, of increased accuracy, and unlikely to get out of repair.

30 A further and highly important object of the invention is to provide manifolding material and feeding means cooperative therewith which will insure increased accuracy of registry and alignment of the strips both longitudinally and transversely.

35 A further and important object of the invention is to provide a manifolding material and feeding means cooperative therewith by which the superposed strips of manifolding material will be more frequently and constantly readjusted as they approach the writing position to insure greater accuracy.

40 A further object of the invention is to provide as an article of manufacture an approved form of manifolding material having relatively staggered marginally punched feed holes which will cooperate with the feeding devices to insure accuracy of registry and alignment.

45 A further object of the invention is to provide as an article of manufacture an improved form of pin type feeding device having relatively staggered feeding pins which will serve to register and align corresponding manifolding material both laterally and longitudinally and which by relative disposition of the feeding pins will effect a more frequent readjustment of superposed record strips fed thereby to maintain a substantially constant condition of registry and alignment.

50 A further object is to provide as articles of manufacture continuous series connected form stationery having a distinctive arrangement of relatively offset marginally punched feed holes and correlated pin type feeding means cooperating therewith.

55 A further object of the invention is to provide means for automatically maintaining registry and alignment of superposed form stationery within narrow limits of variation.

60 A further object of the invention is to provide improved manifolding material and associated pin type feeding means having the advantageous structural features and meritorious characteristics herein mentioned.

65 With the above primary and other incidental

objects in view, as will more fully appear in the specification, the invention consists of the features of construction, and parts and combinations thereof, and the mode of operation or their equivalents, as hereinafter described and set forth in the claims.

In the drawing wherein is shown the preferred but obviously not necessarily the only forms of embodiment of the invention, Fig. 1 is a perspective view of a portion of a manifolding register illustrating the relation of the manifolding material and pin type feeding device forming the subject matter hereof.

Fig. 2 is a perspective view of a portion of a marginally punched record strip embodying the present invention.

Figs. 3 and 4 illustrate portions of record material having different disposition of offset feed holes.

Figs. 5 and 6 are respectively a side and end elevation of one form of pin type feeding device adapted for use with staggered feed holes.

Fig. 7 is a detail view illustrating the relative disarrangement of superposed strips, which is corrected by the present arrangement of feed holes and pins.

Like parts are indicated by similar characters of reference throughout the several views.

For illustrative purposes but with no intent to unduly limit the application or scope of the invention, the present manifolding material has been illustrated in Fig. 1 as is used in a conventional style of autographic register.

It is to be understood that the present invention is applicable to various mechanisms such as tabulating, and computing machines, addressing machines, typewriters, and other apparatus wherein it is desired to positively advance a continuous strip or strips of record material into accurate registry with a writing or imprinting position.

Referring to the drawing, 1 indicates an autographic register having therein revolvable pin wheel feeding means 2. The radially disposed pins 3 of feeding unit 2 are engageable in marginally punched holes in superposed strips 4 of record material for progressively advancing the material past a writing position 5. The marginally punched holes 6 of the record strips 4 are preferably although not necessarily arranged in two parallel longitudinal rows adjacent to each margin of the record material, the succeeding holes being positioned alternately in the respective rows.

As indicated by longitudinal and transverse dot and dash lines in Fig. 2, the succeeding holes 5 are not only offset laterally at each margin, but the holes along one margin of the strip are longitudinally offset relative to those at the opposite side of the strip, as is indicated by the transverse dot and dash line 7-7. Assuming that the line 7-7 represents the writing line, it is to be noted that at the moment a feed hole 6 at one margin of the strip and the feeding pin 3 which may be engaged therein is positioned coincident with such line, assuring accurate registry at the writing point, a feed hole 6 at the opposite side of the strip and the pin which may be engaged therein has passed beyond the line while the succeeding feed hole and the pin engageable therein have not yet reached the writing line. Thus the feeding and aligning impulses are transmitted alternately at opposite margins of the strip and the superposed strips are brought to registry by coaction of the pins and holes first

in one side of the strip and then at the other, the superposed strips being thereby registered at intervals equivalent to half the longitudinal spacing of the feed holes or twice as frequently as when the feed holes are transversely aligned.

In addition to being staggered or offset longitudinally or in the direction of travel, the succeeding holes 6 in the same margin of the strip are alternately offset laterally into two parallel rows as defined by the dot and dash lines 8-8 and 9-9 of Fig. 2. By such offsetting or staggered relation of the feed holes 6 the line of draft or forward feeding impulses are alternated first in line with one row of holes 8-8 and then in line with the other row of holes 9-9. The distance between succeeding holes in each line of draft is greatly increased, being double that ordinarily provided. This is a material advantage, especially when it is necessary to feed a large number of copies by which the drag or strain is increased since it enables the strips to better resist the increased strain and minimizes tearing of the material.

The engagement of the feeding pins in the successively offset holes transmits to the strips a slight transverse jogging impulse in addition to the advance feeding movement which tends to maintain a more accurate alignment of the strips and correct any tendency to side slip. The forms upon superposed strips may be out of registry both laterally and longitudinally as is indicated in the detail view Fig. 7 wherein the relation of corresponding holes of different strips is indicated before engagement therein of the feeding pins. The engagement of the feeding pins therein causes a relative shifting of the strips and during advancement the pin engages the forward edge of the hole of one strip in advance of its engagement with that of another strip and draws one strip slightly forwardly independently of the other strip until the holes are in exact registry when the strips will be further advanced in unison. This operation is repeated as each succeeding pin enters into the overlapped holes of the superposed strips. At the same time the entry of the pin into slightly relative eccentric holes, if the eccentricity is lateral and due to relative side slip of the strips will push one strip aside relative to the other until the holes register. This lateral aligning adjustment is greatly facilitated by the offsetting or staggering of the holes into diagonal relation at each side of the strip.

The forward or longitudinal staggered relation and the lateral staggered relation of the feed holes may be used separately or in combination as found most desirable for particular conditions of use and the character and number of the strips being fed.

In Fig. 2 the feed holes at one side of the strip have been shown as longitudinally staggered relation to those at the opposite side of the strip, and also the holes at each side of the strip have been laterally offset into parallel rows of staggered holes. Figs. 3 and 4 illustrate two different combinations of laterally staggered holes wherein the feed holes at opposite margins of the strip are oppositely disposed, but not longitudinally staggered. In Fig. 3 one pair of feed holes comprising a hole at each margin of the strip are inwardly offset on line 10-10 and the next pair of holes are outwardly offset on line 11-11. The arrangement of holes in Fig. 4 differs in that the holes of one such pair are both offset in the same direction on line 12-12 while

the holes of the succeeding pair are offset in the opposite direction on lines 13-13. In addition to such relative lateral offsetting of the holes as illustrated in Figs. 3 and 4, the series of holes at the opposite margins of the strips may be additionally offset in a longitudinal direction as illustrated in relation with the transverse line 7 of Fig. 2. Various other combinations of holes relatively offset or staggered either longitudinally or transversely or both may be utilized according to the number and character of the record strips and the required degree of accuracy of registration.

The pin type feeding means may be of various forms for example the pins may be retractable and extendible as disclosed in Letters Patent to Sherman, No. 2,000,649, of May 7, 1935, and No. 2,000,651, of May 7, 1935. For simplicity of illustration the feeding device has been illustrated in Figs. 5 and 6 as comprising a pair of relatively spaced pin wheels 14 interconnected by a shaft 15 for unison rotation. Radially disposed about the peripheries of the pin wheels are feeding pins 16 which are alternately offset or staggered in two parallel rows similar to the arrangement of feed holes 6 in the strips to be fed. If the holes at opposite sides of the strips are longitudinally offset or staggered, the pin wheels will be rotatively adjusted relative to each other to present the pins of the respective wheels in unaligned relation. To the contrary if the holes are only laterally offset and not longitudinally staggered, then the pins of the respective wheels are aligned with each other. The feeding unit having staggered feeding pins and the manifold-
ing material having staggered feed holes for engagement of the feeding unit are interdependent and cooperate with each other to effect a common result.

While the record strips have been herein illustrated as having successions of staggered holes arranged in a substantially serpentine line at each side of the strips and correspondingly spaced feeding devices, it is to be understood that the row of feed holes at one side or the other may be omitted and that under certain conditions of use the strips are fed by a single series of feeding pins engageable in feed holes in one margin only of the strips. The operation and effect of the staggered feeding pins engageable in offset or staggered holes is the same as before described. Likewise while only a pin wheel feeding device is shown, other forms of pin type feeding devices well known in the art may be employed in lieu of the specific form of feeding device illustrated.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having in their opposite margins successions of holes for engagement of a pin type feeding and aligning device wherein succeeding holes of each series are staggered in diagonally offset alternating directions and the holes in one margin of the strip are furthermore longitudinally offset relative to those in the opposite margin of the strip. 10
2. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having therein two parallel rows of marginally punched holes for engagement of a pin type feeding and aligning device wherein the succeeding holes of one row are longitudinally offset relative to those of the other row. 15
3. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having in their opposite margins successions of punched holes for engagement of a pin type feeding and aligning device wherein succeeding holes of one series are longitudinally offset relative to those of the other series. 20
4. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having therein a succession of marginally punched holes for engagement of a pin type feeding and aligning device wherein succeeding holes are both laterally and longitudinally offset in relative staggered relation. 25
5. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having in at least one margin thereof two parallel closely adjacent rows of holes for engagement of a pin type feeding and aligning device, the holes comprising the respective rows being longitudinally offset in advance of the holes of the other row. 30
6. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having in their opposite margins longitudinally disposed series of holes for engagement of a pin type feeding and aligning device, the holes in one margin of the strip being longitudinally offset relative to those in the opposite margin and the succeeding holes in each margin being further diagonally offset in alternating directions. 35
7. A manifolding assembly comprising a plurality of superposed record strips having therein longitudinally spaced feed holes, succeeding portions of which are relatively adjusted into registry and alignment and simultaneously advanced into record receiving position by progressive engagement of traveling feeding pins in said longitudinally spaced holes, said strips being characterized by having in each margin thereof a succession of holes for engagement of a pin type feeding and aligning device the holes in each margin being diagonally offset in alternating directions. 40
8. The herein described method of registering and aligning corresponding record receiving areas of superposed strips of manifolding material which are marginally punched for engagement of a pin type feeding and aligning device including the step of transmitting succeeding impulses alternately at one margin and then at the opposite margin of the strip whereby the strip will receive a greater number of feeding and aligning impulses at increased frequency. 45
9. The herein described method of registering and aligning corresponding record receiving areas of superposed strips of manifolding material which are marginally punched for engagement of a pin type feeding and aligning device including the step of transmitting thereto succeeding feeding and aligning impulses alternately in parallel lines of draft. 50
10. The herein described method of registering and aligning corresponding record receiving areas of superposed strips of manifolding material which are marginally punched for engagement of a pin type feeding and aligning device including the step of transmitting thereto succeeding feeding and aligning impulses at alternating offset points whereby there are transmitted to the strips simultaneous advance and lateral adjusting movements. 55
11. The herein described method of registering and aligning corresponding record receiving areas of superposed strips of manifolding material which are marginally punched for engagement of a pin type feeding and aligning device including the step of imparting thereto succeeding lateral impulses in opposite directions simultaneously with the advancement of the strips. 60
12. In a manifolding apparatus operative upon a series of superposed record strips having therein longitudinally spaced feed holes of which successive portions are relatively adjusted into registry and alignment simultaneously with their advancement into record receiving position by progressive engagement of traveling feeding pins in the longitudinally spaced holes thereof, the combination of a series of such strips having therein a succession of staggered holes for engagement of a pin type feeding device of a traveling carrier and a series of feeding pins carried thereby for engagement in the holes of the record strip, succeeding pins of the series being arranged in diagonally offset relation in alternating 65
- 70
- 75

directions substantially in agreement with the staggered relation of the holes in the strips.

13. In a manifolding apparatus operative upon a series of superposed record strips having therein longitudinally spaced feed holes of which successive portions are relatively adjusted into registry and alignment simultaneously with their advancement into record receiving position by progressive engagement of traveling feeding pins in the longitudinally spaced holes thereof, the combination of a series of such strips having therein a succession of holes for engagement of a pin type feeding device, of a pin type feeding and aligning device for cooperation therewith including two parallel series of relatively spaced traveling feeding pins, carrier means therefor, the pins of one series being offset relative to the pins of the other series in the direction of travel.

14. A manifolding assembly including a plurality of relatively adjustable superposed record strips each having a succession of longitudinally spaced record receiving areas to be progressively aligned and registered at a record receiving position with like areas of another strip of the assembly, each strip having therein a succession of spaced feeding holes for engagement of a pin type feeding device simultaneously with its engagement in corresponding holes of another strip, the feeding holes of the respective strips being offset in relatively staggered relation.

15. A manifolding assembly including a plurality of relatively adjustable superposed record strips each having a succession of longitudinally spaced record receiving areas to be progressively

aligned and registered at a record receiving position with like areas of another strip of the assembly, each strip having therein a plurality of relatively spaced feed holes arranged in a serpentine succession for engagement therein of a pin type feeding device simultaneously with its engagement in corresponding holes of another strip of the assembly.

16. A manifolding assembly including a plurality of relatively adjustable superposed record strips each having a succession of longitudinally spaced record receiving areas to be progressively aligned and registered at a record receiving position with like areas of another strip of the assembly, each strip having in at least one margin thereof a serpentine succession of relatively spaced feed holes for engagement therein of a pin type feeding device simultaneously with its engagement in corresponding holes of another strip of the assembly.

17. The combination with a plurality of superposed relatively adjustable record strips each having a succession of longitudinally spaced record receiving areas to be registered and aligned with like areas of other strips at a record receiving position and each having therein a succession of relatively spaced feed holes arranged in serpentine formation longitudinally of the strip, of a coacting pin type feeding device including a succession of relatively staggered traveling feeding pins progressively engageable simultaneously in corresponding feed holes of different strips.

JOHN Q. SHERMAN.
